UNITED STATES PATENT OFFICE.

JOHN A. ST. CLAIR, OF INDIANAPOLIS, INDIANA.

SANDING MACHINE.

Application filed December 7, 1922. Serial No. 605,335.

To all whom it may concern:

Be it known that I, JOHN A. ST. CLAIR, a citizen of the United States, residing at Indianapolis, in the county of Marion and 5 State of Indiana, have invented a new and useful Sanding Machine, of which the following is a specification.

The object of my invention is to produce a machine by means of which articles such 10 as certain types of saw handles, rake and hoe handles, etc., which are symmetrical, or rotatable, about a transportable axis, may be automatically sanded and polished.

The accompanying drawings illustrate my 15 invention. Fig. 1 is a front elevation, and Fig. 2 is a side elevation of a machine embodying my invention.

In the drawings, 10, 10 and 11, 11 indicate two pairs of parallel shafts which, in 20 the present instance, carry pairs of pulleys 10', 10', 10'', 10', 11', 11', 11''. Extending around pulleys 10', 10', is a flexible belt 12 carrying an abrading outer face, and extending around pulleys 11', 11' is a belt 25 13 having a roughened or article-gripping outer face. Conveniently, this may be an abrading face as in the case of belt 12. Shafts 10 and 11 are rotated in the same direction and shaft 10 is rotated at a considerably higher speed than shaft 11. For 30 convenience, in future reference, belt 12 will be designated as the abrading belt and belt 13 as the feed belt.

At a convenient point between the pairs 35 of shafts 10—11, 10—11, I arrange pairs of backing idlers 14, 15, so as to form a throat 16 into which the articles 17, to be sanded, may be directed between the abrading belt 12 and the feed belt 13, the pairs 40 of backing idlers being sufficiently separated to form a fairly constricted throat as compared with the diameter of the articles 17.

Leading to and from throat 16 is an article guide 18 which is conveniently of tubular form and which may, if desired, be a continuous tube, cut away at opposite sides to give access, by the belts 12 and 13, to the interior of the tube at diametrically 50 opposite points.

Guide 18, instead of being set parallel with shafts 10 and 11, is set at a slight angle thereto, although in a plane parallel with the common planes of the two pairs of 55 shafts, the angularity of setting being de-

termined by the rate of automatic feed desired and the direction of movement of the feed belt.

In order to take care of the dust rising from the operation of the apparatus, it is 60 preferable that the abrading belt 12 move downwardly at the abrading point, and consequently the feed belt must move upwardly and the guide is, therefore, inclined upwardly toward its discharge end. 65

In order that the sanding and polishing of the article may be accomplished as a continuous operation, pulleys 10'' and 11'' carry polishing belts 19 and 20 respectively, 70 which are backed with backing idlers like 75 the idlers 14 and 15, and the guide 18 is continued to a point slightly beyond these belts. These belts may be provided with a polishing coating, such for instance as paraffin. 75

The idlers 14 and 15 are preferably carried in suitable supporting blocks which may be adjusted toward and from each other, to vary the size of the throat 16, by means of suitable oppositely threaded 80 adjusting screws 21 and hand wheels 22.

In operation, the operator inserts the end of the article through the guide 18 into the throat 16, whereupon the feed belt causes a rotation and translation of the article 85 along the guide, and the abrading belt abrades the surface in the desired manner, said belt yielding both longitudinally and laterally to conform to the conformation of adjacent portions of the articles as the same 90 are driven past the abrading point.

I claim as my invention:

1. A sanding machine comprising an abrading belt and cooperating feed belt, 95 means for driving said two belts at different speeds and in opposite directions at adjacent portions, and an article guide leading to and from a point between adjacent portions of said belts at an angle, other than right angle, to the direction of travel 100 of one of said belts.

2. A sanding machine comprising an abrading belt and cooperating feed belt, means for driving said two belts at different speeds and in opposite directions at adjacent portions, a pair of backing means co-operating with adjacent portions of the two belts to form an article-receiving throat, and an article guide leading to and from said throat at an angle, other than 110

right angle, to the direction of travel of one of said belts.

3. A sanding machine comprising an abrading belt and cooperating feed belt, 5 means for driving said two belts at different speeds and in opposite directions at adjacent portions, a pair of backing means co-operating with adjacent portions of the two belts to form an article-receiving 10 throat, means for laterally adjusting said backing means, and an article guide leading to and from said throat at an angle, other than right angle, to the direction of travel of one of said belts.

4. A sanding machine comprising an 15 abrading belt and cooperating feed belt, means for driving said two belts at different speeds and in opposite directions at adjacent portions, and an article guide leading to and from a point between adjacent 20 portions of the belt at an angle to the direction of travel of said belts.

In witness whereof, I have hereunto set my hand at Indianapolis, Indiana, this 4th day of December, A. D. one thousand nine 25 hundred and twenty two.

JOHN A. ST. CLAIR
